UNITED STATES PATENT OFFICE.

DAVID FELTEN, OF PARSONS, KANSAS.

AIR-BRAKE SYSTEM.

No. 826,322.

Specification of Letters Patent.

Patented July 17, 1906.

Application filed November 25, 1905. Serial No. 289,139.

To all whom it may concern:

Be it known that I, DAVID FELTEN, a citizen of the United States of America, residing at Parsons, in the county of Labette and 5 State of Kansas, have invented new and useful Improvements in Air-Brake Systems, of which the following is a specification.

This invention relates to a governor-valve mechanism for automatic air-brake systems, 10 and particularly to valve mechanism for controlling the pressure in the brake-cylinder and for permitting the auxiliary reservoir to be recharged without releasing the brakes.

15 The main object of the invention is to provide a valve mechanism having an exhaust-controller communicating with the exhaust-port of the triple valve and governed in action by operating means subjected to and 20 controlled by auxiliary-reservoir pressure, whereby the auxiliary reservoir may be recharged while the brakes are set during a service or emergency application without reducing the brake-cylinder pressure and releasing the brakes, and, further, whereby the 25 maximum reservoir-pressure may be varied as desired to meet different requirements of service.

Another object of the invention is to provide 30 a governor-valve mechanism provided with means whereby the maximum auxiliary-reservoir pressure may be varied and maintained at the desired pressure while the brakes are set and by which also relief will 35 be afforded when the established pressure is exceeded to prevent undue braking pressure on the wheels of the car and the well-known deleterious actions resulting therefrom.

40 The accompanying drawing shows, partly in diagram and partly in section, the essential elements of the ordinary automatic air-brake mechanism with my regulating-valve devices in operative connection therewith, 45 the parts being in service position and the pressure-regulating valve in the position it occupies when the brake-cylinder is overcharged.

The numeral 1 designates the train-pipe; 50 2, the triple valve; 3, the auxiliary reservoir; 4, the usual pipe connection between the triple valve and auxiliary reservoir; 5, the brake-cylinder, and 6 the usual feed and release pipe leading from the triple valve to the brake-cylinder.

55 My improved valve mechanism comprises

regulating and pressure-controlling valves, the regulating-valve performing the function of a recharging-valve to permit the auxiliary reservoir to be recharged to normal pressure 60 after the brakes are set without releasing the brakes. These valves are arranged within a common casing having chambers for their reception, this being the preferred construction, although of course it will be understood that separate casings for the valve devices may be employed. As shown in the present instance, a chambered casting 7 is provided, which is formed on one side with a chamber or compartment 8 and a smaller 70 chamber or compartment 9 disposed in axial alignment therewith, said chambers being separated by a wall or diaphragm 10, supporting a stuffing-box 11. Within the chamber 8 is a bushing 12, in which operates a 75 diaphragm or piston 13, provided with suitable packing-rings, and mounted upon the intermediate portion of a stem 14, sliding through the stuffing-box and projecting at one end into the chamber 9 and at its opposite end through an opening in the bottom wall or head 15 of the chamber 8 into a tubular extension 16, carried by said wall or head. The wall of the chamber 9 and the 80 said tubular extension 16 are internally 85 threaded for the reception of threaded plugs or nuts 17 and 18, the plug 17 being provided with a valve-seat 19 and an exhaust-port 20 leading therefrom to the atmosphere, while the plug 18 is formed with a cavity 21 90 for the reception of the lower end of the stem 14, which is free to slide therein and guided thereby. The stem is provided at its upper end with a valve 22 to engage the seat 19, and thus cut off communication between 95 the chamber 9 and the atmosphere, while the piston 12 is formed at its base with a boss or stop member 23 to engage the wall 15 and limit its downward movement. A coiled pressure-regulating spring 24 surrounds the 100 stem between said boss and the plug or nut 18 and serves to force the piston upward in the chamber 8. The resistance of this spring to the downward movement of the piston may be regulated by adjusting the nut 18. 105 The wall 15 is formed with a vent-aperture 25 to permit any air which may pass below the piston to escape to the atmosphere and prevent atmospheric resistance to the movement of the piston.

110 For sake of clearness of description the parts of the device will be described in the

following specification and claims as though the elements of the valve mechanism were arranged in a vertical position, thus assuming that the chamber 9 is disposed above the chamber 8; but it will of course be understood that in practice the parts may be either vertically or horizontally disposed, as circumstances or requirements may demand.

The chamber 8 is in communication above 10 the piston 13 with a pipe 26, leading to the auxiliary reservoir 3, and provided with a valve 27 for a purpose hereinafter described. This valve is normally left open for free communication between said chamber and reservoir, so that the piston 13 will be exposed 15 on one side to auxiliary-reservoir pressure and on its reverse side to the pressure of the regulating-spring 24, which resists the downward movement of the piston under such reservoir-pressure. The chamber 9 communicates by a pipe 28 with the exhaust-port of 20 the triple valve 2, which pipe is provided with a valve 29. The valve 29 is of the two-way type, and its casing is provided with an outlet 30, leading to the atmosphere, the construction of the valve being such that when turned to one position it will cut off said outlet and open communication between the chamber 9 and triple valve and when turned to another 25 position will cut off communication between said chamber 9 and the triple valve and open direct communication between the triple valve and the atmosphere. By means of the valves 27 and 29 the regulating or recharging valve may be cut out of connection 30 with the air-brake system, and the exhaust from the triple permitted to vent to the atmosphere through the outlet 30. If, therefore, from any cause the spring 24 should 35 break or the valve mechanism otherwise rendered inoperative, said valve mechanism may be thrown out of communication with the air-brake system and the latter permitted to operate in the usual way.

40 It will be understood from the foregoing description that the exhaust from the triple will be normally confined and will be controlled by the valve 22 and that the piston 13 will be exposed on its upper side continually to auxiliary-reservoir pressure. When 45 the brakes are applied by the movement of the triple valve to either service or emergency position, the pressure in the brake-cylinder will be retained and air allowed to feed to the auxiliary reservoir until recharged 50 to its full pressure, as the escape of air from the brake-cylinder through the triple valve will be arrested by the valve 22. When the 55 pressure in the auxiliary reservoir reaches the maximum, the pressure in the upper portion 60 of the chamber 8 will balance the pressure of the spring 24, and upon an augmentation of pressure in the reservoir the piston 13 will be forced down against the resistance of 65 the spring, thus opening the valve 22, so as to

reopen communication between the brake-cylinder and atmosphere through the triple valve to permit of the release of the brakes. It will thus be apparent that the auxiliary reservoir may be recharged without releasing 70 the brakes and that by regulating the resistance of the spring 24 through the medium of the nut 18 the valve mechanism may be rendered capable of operation to adapt the auxiliary reservoir to be charged to any desired working pressure. By normally maintaining the auxiliary - reservoir pressure slightly below that required to effect the movement of the piston against the resistance of the spring the brakes may be held applied with 80 the required degree of pressure for any desired period and released by the adjustment of the engineer's brake-valve to augment the pressure in the train-line to a sufficient extent to overbalance or overcome the resistance of the spring. 85

The casting 7 is provided upon its opposite side with a chamber 31, closed at its upper end by a head 32, having an extension 33 and a vent-aperture 34, conforming in construction 90 and function with the parts 16 and 25 previously described. The bottom wall of said chamber is also formed with an internally-threaded extension 35, receiving an adjustable threaded plug 36, having a valve-seat 95 37 and an escape-port 38, while a threaded plug or nut 39, conforming in construction to the plug 18, before described, fits within the said extension 33. Operating in a bushing 40 in the chamber 31 is a pressure retaining 100 and controlling piston 41, carried by a stem 42, carrying at its lower end a valve 43, governing the port 37 and movable at its upper end in the cavity 44 in the plug 39. The piston 41 operates in a reverse direction to the piston 13 and is normally forced downward by a pressure-regulating spring 44, adjustable to regulate its resistance through the medium of the plug or nut 39. Below the piston the chamber 31 is in communication 105 with the brake-cylinder 5 through an exhaust-pipe 45, in which is arranged a valve 46, whereby the retaining-valve may be thrown out of communication with the brake-cylinder when its use is not desired or whenever it is rendered inoperative through breakage of any of its parts. The valve 43 is normally held closed by the spring 44 against the pressure of air in the lower portion of the chamber 1 from the brake-cylinder, thus normally retaining in said cylinder a determined air-pressure, which may be regulated as desired within prescribed limits by varying the resistance of the spring 44. When the pressure in the brake-cylinder exceeds 115 120 that for which the retaining-valve is set, the piston 41 will be moved upward and the valve 43 opened to permit the excess of pressure to exhaust to the atmosphere, after which the valve will be closed to maintain within the 125 130

brake-cylinder the working pressure desired. It will be apparent, therefore, that the maximum braking pressure may be regulated to suit the weight of the load controlled thereby, thus enabling lightly and heavily loaded cars and mixed trains to be kept under ready control in descending grades.

The port 38 may be of restricted size to allow the excess air-pressure in the brake-cylinder to escape slowly to the atmosphere in order to adapt the device for use as a high-speed brake. The slow reduction of pressure in the brake-cylinder, due to the small size of the port 38, will maintain the brakes in engagement with the wheels of a train running at a rapid rate of speed until the speed is reduced to a certain degree, at which time the excess of pressure will have exhausted from the brake-cylinder and the valve 43 moved to closed position. By this means a safe control of high-speed trains may be secured and a safe limited braking pressure left within the brake-cylinder when the speed of the train is reduced to the desired rate to prevent locking and sliding of the wheels.

While I have disclosed one form of embodiment of my invention, it will of course be understood that any variation preserving the functional characteristic of that shown may be made without departing from the spirit of the invention.

Having thus described the invention, what is claimed as new is—

1. In an air-brake system, a regulating valve comprising a casing having two chambers separated by a partition, one of said chambers being provided with an outlet-port, a stem arranged in said chambers and sliding through said partition, a diaphragm arranged within the other chamber, means for subjecting the diaphragm to pressure on its side adjacent the partition, a spring acting on the opposite side of the diaphragm in opposition to such pressure, means for connecting the other chamber with the exhaust-port of the triple valve, and a valve carried by the stem and operating in said chamber to close the outlet-port therein.

2. In an air-brake system, a regulating

valve comprising a casing having two non-communicating chambers, said chambers being separated by an intermediate partition, and each having a tubular extension, plugs closing the tubular extensions and adjustably mounted therein, one of said plugs being provided with an outlet, a stem projecting through the partition and chambers and provided in one of said chambers with a valve controlling said outlet, means for connecting said chamber with the exhaust-port of the triple valve, a diaphragm fixed to the stem within the other chamber, means for admitting auxiliary-reservoir pressure to said chamber to act upon said diaphragm, and a spring arranged between the other side of the diaphragm and the plug in the tubular extension of said chamber to oppose resistance to such pressure, substantially as described.

3. In a governing-valve for air-brake systems, a casing, a piston operating therein, said casing being provided with means for subjecting the piston to air-pressure on one side, adjustable nuts carried by the casing, one of said nuts having an exhaust-port and a valve-seat and the other a guide-socket, a stem connected with the piston and provided at one end with a valve to engage the said seat and control the said exhaust-port and movable at its opposite end in said guide-socket, and a spring between the socketed nut and piston exerting pressure to hold the valve closed against the air-pressure, substantially as described.

4. In an automatic air-brake system, a valve controlling the exhaust from the brake-cylinder through the triple valve, a piston directly connected with said valve to move in unison therewith, a spring exerting pressure on one side of the piston to hold the valve closed, and means for subjecting the reverse side of the piston to counteracting auxiliary-reservoir pressure.

In testimony whereof I affix my signature in presence of two witnesses.

DAVID FELTEN.
